(57) **CLAIM**

The ornamental design for a data storage device holder as shown and described.

DESCRIPTION

FIG. 1 is a rear-right perspective view of a data storage device holder.

FIG. 2 is a top view of the data storage device holder of FIG. 1.

FIG. 3 is a cross-sectional view along lines 3-3 in FIG. 2. FIG. 4 is a left-side view of the data storage device holder of FIG. 1, which is the same as the right-side view of the data storage device holder of FIG. 1.

FIG. 5 is a bottom view of the data storage device holder of FIG. 1; and,

FIG. 6 is a front view of the data storage device holder of FIG. 1, which is the same as the rear view of the data storage device holder of FIG. 1.

The broken lines shown in the data storage device holder form no part of the claimed design.
